UNITED STATES PATENT OFFICE

ROBERT E. FLEMING, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed July 30, 1927. Serial No. 209,561.

This invention relates to refrigerating apparatus, particularly small household or commercial plants of the compressor-condenser-expander type.

5 One of the objects of the invention is to improve the construction and arrangement of the condenser to make possible more effective cooling.

Another object is to arrange the condenser 10 to facilitate the circulation of air.

Another object is to reduce the noise formerly characteristic of air cooled plants of this type.

Another object is to provide an improved 15 and compact machine unit for refrigerating systems.

Still another object is to construct a condenser of units or sections to enable the capacity of the condenser to be readily increased without requiring new coils, forms or 20 the like.

Further objects and advantages of the present invention will be apparent from the following description, reference being had to 25 the accompanying drawings, wherein a preferred form of the present invention is clearly shown.

In the drawings

Fig. 1 is a front elevation of a refrigerating 30 apparatus embodying one form of my invention, the system to which it is applied being indicated diagrammatically,

Fig. 2 is a plan of a portion of the apparatus shown in Fig. 1, and

5 Fig. 3 is a section on the line 3—3 of Fig. 2.

Referring to Fig. 1, the system comprises a conventional compressor 10, driven by a motor 11, which draws gaseous refrigerant from an evaporator diagrammatically represented at 13 and delivers it in compressed gaseous form to a condenser generally denoted by 14. The refrigerant condenses to liquid and flows to a receiver 15 (Fig. 3), the liquid being forced into the evaporator 40 by the pressure developed by the compressor. 45

The motor is automatically started and stopped in response to conditions in the system by a pressure responsive switch 16.

In order to cool the compressed refrigerant effectively with air, it is necessary to have a condenser of large surface compared to the volume of refrigerant it contains. The usual manner of constructing such a condenser has been to provide one or more coils 20 wound of tubing of small bore, for example of the order of $\frac{1}{4}$ of an inch. Frequently the tubing is flattened to provide more surface per unit volume. It has been customary to provide two such coils, and to cool them by placing one at either side of the motor and 55 placing a fan 15 on the motor shaft. The fan blows air over the coils, the motor serving to deflect the air thru the coils somewhat, as shown by the arrows in Fig. 2.

The apparatus thus far described is preferably arranged with the compressor, motor and condenser mounted on the upper side of a base 12, while the receiver 15 is mounted on the lower side of the base. The base may be suitably fabricated from angle iron members 13 and may have legs 14 by which it is supported. Each coil of the condenser may be supported by suitable upright members 21 shown best in Fig. 3, which are clamped to the base 12 as shown in Fig. 1. 75

The condensers heretofore made have been objectionable for two reasons:

First, the fan required was so large that it made an objectionable noise.

Second, the air currents did not reach all 80 parts of the condenser tubing, hence a large portion of the condenser was ineffective to liquefy the refrigerant.

In order to remedy these defects, I provide means whereby the air set in motion by the fan is carried to all parts of the condenser and thus the effectiveness of the condenser is increased. This permits the size of the fan to be reduced and permits multiplication of the condenser units or coils without sacrificing 85 90

efficiency. As shown in Figs. 2 and 3, the coils are arranged parallel to the motor shaft, with the fan at one end of the coils. At the other end of the coils, that is opposite the fan, I arrange a baffle 30. As shown best in Fig. 2, this baffle extends entirely across the condenser and has its ends 31 turned forward in the direction of the fan so as to overlap the coils 20. To enable the baffle to be placed close to the condenser coils, it may have a dished or recessed portion 32 which receives the projection 33 commonly a part of motors used for this purpose. The ends 31 of the baffle deflect the air currents, which pass between the condenser coils, around the ends of the coils and back thru the coils as shown by the arrows in Fig. 2. Some air currents are deflected upwardly by the body of the motor, and these are prevented from escaping, except by passing through the condenser coils, by the lip 33 which may be formed integrally with the baffle, and which extends horizontally above the motor substantially the entire distance between the groups of coils. Thus any air deflected upwardly by the motor is deflected laterally and passes thru the coils as shown by the arrows in Fig. 1.

The ends of the condenser coils remote from the fan are, in previously known apparatus out of the path of air currents, the air either passing along the motor between the coils, or being deflected thru the coils before it reaches the ends. These remote ends of the coils in my arrangement are completely bathed in air currents.

This enables me to increase the capacity of the condenser simply by using two or more coils 20 on each side of the motor, because all parts of all of the coils are effectively cooled by air currents. This is a considerable advantage when it is occasionally desired to make a condenser of large capacity. A single size of coil, made from the same form, is all that is needed, both for condensers of large and of small capacities. This saves factory equipment and storage space, and reduces the number of stock coils necessary to be kept on hand.

The baffle may be supported in any convenient manner, but the preferred manner of supporting it is shown in the drawings, especially Fig. 3. The motor is mounted substantially at the vertical center of the condenser coils. To accomplish this, it is elevated somewhat above the base 12. The motor itself is supported on a sub-base, formed of two angle-irons 35 which are supported above the base 13 by being secured by rivets 36 (Fig. 1) to the uprights 37 of two U-shaped supports 38 which rest on, and are suitably fastened to the angle-irons 13. At the side away from the fan 15, the supports 38 are formed with horizontal extensions 40 which furnish support for the baffle. The lat-

ter is formed with a horizontal lip 41, which may be integral with it, and which may be reinforced by an angle-iron 42 welded to the baffle. The lip 41 is bolted to the extensions 40 by bolts 42a. The upper baffle or lip 33 may be formed with a stiffening rib 43, and may be bolted by bolts 44 to a cross bar 45 supported on the uprights 21 which support the coils.

Preferably the motor drives the compressor by means of a belt 50 and pulley wheels 51 and 52. The belt as well as the fan are enclosed by a guard 53 which may be covered by wire mesh as indicated at 54 in Fig. A.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising in combination, a motor, a condenser including cooling conduits arranged on opposite sides of the motor, a fan driven by the motor for cooling the condenser, the motor being arranged to deflect the air moved by the fan, and means above the motor for directing upwardly deflected air in contact with the conduits.

2. Refrigerating apparatus comprising in combination, a condenser including spaced heat exchange devices, a fan at one end of the condenser, and a baffle extending across the other end of the condenser, said baffle being disposed close to the condenser, said baffle having a recessed portion between the devices adapted to receive a motor for driving the fan.

3. Refrigerating apparatus including in combination a condenser, a fan mounted at one end of the condenser, and a baffle at the other end of the condenser arranged to deflect over the condenser air blowing through the condenser, said baffle having portions extending toward the fan at the sides of the condenser.

4. Refrigerating apparatus including in combination a condenser, a fan mounted at one end of the condenser and a baffle at the other end of the condenser arranged to deflect over the condenser air blowing through the condenser, said baffle having a portion turned toward the fan at the top of the condenser.

5. Refrigerating apparatus including in combination, a condenser, a fan mounted at one end of the condenser and a U-shaped baffle at the other end of the condenser extending entirely across the condenser and arranged to deflect over the condenser air blowing through the condenser, said baffle having its ends overlapping the condenser in the direction of the fan.

6. Refrigerating apparatus including in combination a condenser having spaced heat

exchange devices, a fan for cooling the condenser having its axis located between said devices, a baffle extending across the condenser at the end opposite the fan and disposed transverse to the axis of the fan, and a second baffle disposed between the devices and substantially parallel to the axis of the fan.

5 In testimony whereof I hereto affix my
10 signature.

ROBERT E. FLEMING.
